W. L. BORATE

SUPPORT FOR INCANDESCENT LAMPS

Filed April 16, 1925

UNITED STATES PATENT OFFICE.

WILLIAM LOUIS BORATE, OF ROCHESTER, NEW YORK.

SUPPORT FOR INCANDESCENT LAMPS.

Application filed April 16, 1925. Serial No. 23,516.

To all whom it may concern:

Be it known that I, WILLIAM LOUIS BORATE, a citizen of the United States, and resident of Rochester, in the county of Monroe and State of New York, have invented certain new and useful Improvements in Supports for Incandescent Lamps, of which the following is a specification.

The present invention relates to supports for incandescent lamps and an object thereof is to provide a simple and inexpensive construction which may be employed for supporting an incandescent lamp arranged on the end of a cord so that the bulb may be held in a fixed position, projecting upwardly from the socket.

To this and other ends, the invention consists of certain parts and combinations of parts, all of which will be hereinafter described: the novel features being pointed out in the appended claims.

In the drawings:—

Fig. 1 is a plan view of the support with parts broken away;

Fig. 2 is a section on the line 2—2, Fig. 1, showing the lamp in position with a shade on the shade support;

Fig. 3 is an enlarged section on the line 3—3, Fig. 1;

Fig. 4 is a fragmentary detail view showing the connection between the lamp supporting ring and the legs; and

Fig. 5 is a side view of another embodiment of the invention.

In the illustrated embodiment of the invention there is employed a lamp engaging member comprising, in this instance, a ring 1 split at 2 to resiliently engage about the socket 3 of an electric incandescent lamp 4.

This ring has arms extending radially therefrom and formed by bending the wire stock or strip from which the ring is made to provide loops 5 which add also to the resiliency of the ring. These radial loops 5 have the

two longitudinally extending portions thereof wrapped with a piece of sheet material to provide sleeves, as at 6, and between the two longitudinally extending portions, the sheet material is bent into a sleeve 7 lying to one side of the sleeves 6 surrounding the two longitudinally extending portions 5. This sleeve is adapted to receive a portion of a support for the lamp holder.

One of such supports is shown in Figs. 1 to 4, inclusive, and comprises a leg em-

bodying, in this instance, two sections 8 and 9, connected together in telescoping relation by a resilient double sleeve 10, which receives both of the portions 8 and 9 and holds them in an adjusted position in such sleeve 60 while permitting the adjustment of the sleeve on both portions to vary the length of the leg or support. The upper end of the portion 9, in this instance, has two parallel portions 11 and 12, preferably lying at an obtuse angle to the length of the support 65 and connected by a bend 13. The portion 12 is adapted to pass through the sleeve 7 and is greater in diameter than the distance between the sleeve 6, while the portion 11 70 is adapted to fit partially in the space between the sleeves 6, so that a bracing relation with the sleeves 6 is established. When the lamp is in the socket, the legs or supports cannot be removed or become accidentally displaced due to the fact that in removing them, they must move inwardly 75 into the space occupied by the socket 3. In other words the lamp socket acts as a locking means for holding the legs or supports 80 to the lamp holder.

The lamp holder also acts as a support for a lamp shade holder, which comprises a ring 14 supporting the shade 15 and formed from the same piece of wire from which the lamp holder 1 is formed, being supported above the lamp holder by an upright portion 16 extending from the ring 1 to one side of the split tube upwardly and inwardly at 17 to the ring 14. 90

Instead of supporting the lamp holder by the legs shown in Figs. 1 to 4, supports 18 may be employed fitted in the outer ends of the sleeves 7 and having downwardly turned ends 19. These supports are adapted 95 to rest upon the upper edge of a vase 20, as shown in Fig. 5, the downwardly turned portion preventing the lateral displacement of the lamp holder on the vase, the cord, of course, in this instance, passing into the 100 vase through the top thereof between the supports.

From the foregoing it will be seen that there has been provided an incandescent lamp support having a resilient ring adapted 105 to be clamped about the socket of an incandescent lamp and provided with radially extending portions with which legs or supports are adapted to be detachably engaged. These radially extending portions are formed by 110

loops in a piece of wire which also forms the lamp holding ring. Each of these loops support to one side of the plane thereof a sleeve in which the supporting devices engage, this sleeve opening at opposite ends so that the supporting devices may enter from either end. One set of the supporting devices has two parallel portions connected by a bend so that when one of these parallel portions is passed through the sleeve from the inner end thereof, the other will engage with the underside of the loop. This connection between the supports is held in a locked condition by the socket of the electric lamp or bulb fitting in the lamp supporting ring.

What I claim as my invention and desire to secure by Letters Patent is:—

1. A support for incandescent lamps comprising a resilient lamp supporting ring having arms extending outwardly therefrom and provided with sleeves, and supports removably fitted in said sleeves.
2. A support for incandescent lamps comprising a resilient lamp supporting ring, looped arms extending outwardly from said ring and formed from a strip of wire which also forms the ring, and supports detachably connected with said looped arms.
3. A support for incandescent lamps comprising a resilient lamp holding ring, open ended tubes extending outwardly from said

lamp holding ring, and supports removably fitted in said tubes.

4. A support for incandescent lamps comprising a resilient lamp holding ring, open ended tubes extending outwardly from said lamp holding ring, and supports removably fitted in said tubes, said supports having portions entering the tubes from the inner ends thereof and held against removal by a lamp socket in the resilient lamp holding ring.

5. A support for incandescent lamps comprising a resilient ring shaped center portion, loops extending radially from the center portion, open ended pieces each rolled about the two arms of a loop and forming an open ended sleeve to one side of a loop, and supports removably fitted in said sleeves.

6. A support for incandescent lamps comprising a center ring shaped resilient lamp holding portion, having loops extending radially therefrom, and supports detachably connected to said loops.

7. A support for incandescent lamps comprising a resilient lamp holding ring formed from a single piece of wire, a lamp shade support formed in one piece with the lamp holding ring extending upwardly therefrom, and having a shade engaging ring at its upper end.

WILLIAM LOUIS BORATE.
